UNITED STATES PATENT OFFICE.

JOHN M. PITTS, OF POPLAR SPRINGS P. O., GEORGIA.

PLOW-STOCK.

SPECIFICATION forming part of Letters Patent No. 244,660, dated July 19, 1881.

Application filed May 23, 1881. (No model.)

To all whom it may concern:

Be it known that I, JOHN MONTGOMERY PITTS, a citizen of the United States, residing at Poplar Springs P. O., in the county of Har-
5 also and State of Georgia, have invented certain new and useful Improvements in a cer-
tain Iron-Foot Plow-Stock; and I do hereby declare that the following is a full, clear, and exact description of the same, reference being
10 had to the annexed drawing, making a part of this specification, and to the letters and figures of reference marked thereon.

The present invention has relation to certain new and useful improvements in plows; and
15 it consists in the manner of connecting the standard with the brace, whereby increased strength and durability are obtained and a more perfect and rigid connection is formed between the brace and standard. These objects I at-
20 tain by the construction shown in the drawing and hereinafter described.

In the accompanying drawing, which represents a perspective view of my invention, A is the plow-beam, B the standard, and C the brace, all of which are constructed of metal.
25 The beam A has suitable handles connected to it, and the standard B is so formed as to embrace both sides of the beam at its upper ends, to which said standard is pivoted. The
30 curved brace C in like manner embraces the rear end of the plow-beam, and is adjustably connected thereto by a suitable bolt entering one of a series of holes, a, and passing through a corresponding hole in the beam. These parts,
35 so far as described, are similar in form and construction to those in common use; but instead of connecting the lower end of the curved brace C directly to the standard B, as heretofore, I

pivot to said standard a toggle-arm, b, the opposite end thereof being rigidly connected to the lower end of the adjustable brace C. By the addition of the toggle-arm b increased strength is obtained, as the pivotal point is extended much nearer the plow-beam, which leaves the standard more firm and rigid than were the pivotal point of connection on the same line of meeting, between the end of brace and standard, as all the strain of the standard, by the use of the toggle-arm b, works back against the shoulders or end of the brace, against which it comes in contact, thus the strain upon the rivet that connects the toggle-arm to the standard being entirely removed. This manner of connecting the brace to the standard by the employment of an intermediate device in the form of a toggle-arm adds great strength to the plow, and also enables the standard to be raised or lowered, as circumstances may require, by the adjustment of the brace upon the rear end of the plow-beam.

Having now fully described my invention, what I claim as new, and desire to secure by Letters Patent, is—

The plow-beam A, having pivoted thereto the standard B, in combination with the adjustable brace C, and toggle-arm b, rigidly connected to the lower end of the brace and pivoted to the standard, substantially as and for the purpose set forth.

In testimony that I claim the above I have hereunto subscribed my name in the presence of two witnesses.

JOHN MONTGOMERY PITTS.
